UNITED STATES PATENT OFFICE.

GUY C. CROSS, OF DENVER, COLORADO.

PHOTOGRAPHIC FILM RACK.

1,422,341.

Specification of Letters Patent. Patented July 11, 1922.

Original application filed January 8, 1920, Serial No. 350,201. Divided and this application filed September 21, 1920. Serial No. 411,699.

To all whom it may concern:

Be it known that I, GUY C. CROSS, a citizen of the United States, residing at Denver, in the county of Denver and State of Colorado, have invented new and useful Improvements in Photographic Film Racks, of which the following is a specification.

The present invention is directed to improvements in film rack, and has for its object to provide a device of this character so constructed that the film strips will be firmly secured thereto during the successive operations of developing, fixing, washing and drying, but may be readily removed when desired.

A further object of the invention is to provide a rack of this nature having associated therewith a clamping bar which co-operates with the rack to impale the film strips thereto to prevent accidental disengagement thereof during handling.

The rack is designed particularly for use in connection with the film strip hanger or loader described in my co-pending application Serial Number 350,201, filed January 8, 1920, of which this application is a division.

With these and other objects in view, this invention resides in the novel features of construction, formation, combination and arrangement of parts to be hereinafter more fully described, claimed and illustrated.

An embodiment of the invention that is considered the preferable one, is illustrated in the accompanying drawing, wherein:

Figure 1 is a perspective view of the device.

Figure 2 is a vertical sectional view through the device.

Figure 3 is a fragmentary bottom plan view.

The rack comprises a U-shaped frame 1, formed from suitable gauge wire, and has its horizontal bar 2 provided with a plurality of equally spaced spurs 3.

The vertical bars 4 of the frame 1 terminate in outwardly directed horizontal arms 5, which are designed to rest in the usual manner on the conventional tanks so that the films engaged on the rack will be suspended in the solution contained in the tank.

The arms 5 terminate in loops 6 which

constitute handles so that the rack can be conveniently handled.

The clamping bar 7 is formed from angle iron, the horizontal web 8 thereof having its ends formed with guides 9 for slidably engaging the vertical bars 4 of the rack, said web being further provided with a plurality of perforations 10, corresponding in number to the spurs 3, the purpose of which will appear later.

The vertical web 11 of the clamping bar is so arranged that it will lie close to the bar 2 of the frame when said bar is in its lowermost or operative position.

In operation, the film strips 12 are placed with their upper ends resting on the spurs 3, whereupon the clamping bar 7 is moved downwardly, which action causes the spurs to penetrate the films and enter the perforations 10, thus firmly securing the strips to the rack.

Since the vertical web 11 of the bar 7 lies adjacent the bar 2 of the rack it is obvious that the same will cause the upper end of the film strip to curl over the bar 2 and hold the extreme upper end of the strip in binding engagement with the bar 2, as clearly shown in Fig. 2 of the drawing.

Thus it will be seen that the film strips will be impaled on the spurs 3, and cannot be removed until the clamping bar 7 is elevated to its inoperative position, as shown in dotted lines in Fig. 1 of the drawing.

It will be noted that the ends of the vertical web 11 of the bar 7 is curved, as at 13, and has its upper edge in contact with the adjacent part of the horizontal web 9 and suitably secured thereto, thus bracing the respective webs.

What is claimed is:

1. As a new article of manufacture, a film rack comprising a U-shaped frame, a clamping bar having guides carried by its ends for slidably engaging the side bars of the frame, said side bars terminating in horizontal arms, as and for the purpose set forth.

2. As a new article of manufacture, a film rack comprising a U-shaped frame having its bight portion provided with a plurality of spurs, a clamping bar slidably engaged with the side bars of the frame, and movable towards and away from the bight por-

tion to hold film strips engaged therewith and impaled on the spurs, said side bars terminating in horizontal arms having handles carried thereby, as and for the purpose set forth.

3. As a new article of manufacture, a film rack comprising a U-shaped frame, the bight portion thereof having spurs carried thereby, a clamping bar comprising vertical and 10 horizontal webs, the latter having guides and perforations formed therein, the guides being adapted to slidably engage the side bars of the frame, said vertical web being

adapted to hold the film strips in binding engagement with the bight portion when the 15 spurs are engaged in said perforations and in penetrating engagement with the film strips.

In testimony whereof I have hereunto set my hand in presence of two subscribing witnesses.

GUY C. CROSS.
